UNITED STATES PATENT OFFICE

139,580

DESIGN FOR A MOLDED INSOLE

Fred J. Diamant, New York, N. Y.

Application April 5, 1944, Serial No. 113,151

Term of patent 14 years

(Cl. D7—5)

To all whom it may concern:

Be it known that I, Fred J. Diamant, a citizen of no country, residing in the city of New York, county of New York, and State of New York, have invented a new, original, and ornamental Design for a Molded Insole, of which the following is a specification, reference being had to the accompanying drawing, forming part thereof.

Fig. 1 is a perspective view of a molded insole showing my new design.

Fig. 2 is a perspective view of the molded insole showing the opposite side of the insole as shown in Fig. 1.

Fig. 3 is a bottom perspective view of the molded insole as shown in Fig. 2.

I claim:

The ornamental design for a molded insole, substantially as shown.

FRED J. DIAMANT.
